ATTORNEY

UNITED STATES PATENT OFFICE.

THOMAS SLATTER, OF SAN FRANCISCO, CALIFORNIA.

FOLDING UMBRELLA.

1,139,913.

Specification of Letters Patent. Patented May 18, 1915.

Application filed September 15, 1914. Serial No. 861,794.

To all whom it may concern:

Be it known that I, THOMAS SLATTER, a subject of the King of England, residing in the city and county of San Francisco and State of California, have invented new and useful Improvements in Folding Umbrellas, of which the following is a specification.

This invention relates to foldable umbrellas, parasols, and the like, and more particularly to improvements over Patents 10 #1,042,522 and #1,045,358, invented by J. Aragall and assigned to me.

The object of the present invention is to simplify and improve the construction 15 shown in the former patents, and particularly to provide a more rigid and simple locking mechanism between the umbrella rod and handle.

Further objects will hereinafter appear. 20 The invention consists of the parts and the construction and combination of parts as hereinafter more fully described and claimed, having reference to the accompanying drawings, in which—

25 Figure 1 is a central vertical section showing the umbrella assembled. Fig. 2 is a similar section showing the umbrella in the folded or dissembled position. Fig. 3 is a detail exterior view looking at right angles 30 to Fig. 1. Fig. 4 is a cross-section on line 4—4, Fig. 1. Fig. 5 is a detail view of the handle section.

The umbrella consists primarily of a handle section A, a tubular rod 2, and a rod 35 extension or tip 3. The ribs and stretchers of the umbrella together with the covering are secured to the tubular rod in the usual manner as at 4, and the upper and lower latches 5 and 6 are provided to secure the 40 ribs in the extended or folded position. The rod extension is foldable with relation to the tubular rod and the umbrella handle is detachable with relation to same to reduce the structure as a whole in length as much as 45 possible for convenience of packing, carrying, etc. and this is accomplished in the following manner: Suitably secured to the handle A is a short rod extension 7 and mounted in said rod is a spring actuated 50 latch member 8. Rod 7 is inserted in the upper end of the tubular rod when the handle is attached and a slot 9 is formed at this point with which the latch engages to form a lock between the tubular rod and 55 handle. For the purpose of reinforcing and strengthening the connection formed be-

tween the tubular rod and handle and also for the purpose of providing means by which the extension rod 3 may be actuated and secured, a sleeve member 10 has been 60 provided. This sleeve is slidably mounted on the exterior of the tubular rod 2 and the movement of same is limited in one direction by a pin 11 which passes through a pair of slots 12 formed in the tubular rod, and in 65 the opposite direction by latch 8 and handle A. A flexible connection is formed between pin 11 with connected sleeve 10 and the lower rod extension 3 by a wire rod 13 and a pair of links 14 and 15. By sliding sleeve 70 10 downwardly on the tubular rod, or away from the handle, movement is transmitted through rod 13 and links 14 and 15 to force extension 3 out of the lower end of the tubular rod, and links 14 and 15 will then permit 75 the extension to be folded over, as shown at 16 in Fig. 2, thus shortening the umbrella structure considerably. An upward pull on the sleeve will draw the rod extension 3 back into the tubular rod and the sleeve will at 80 the same time pass over latch 8 and become engaged by same. Latch 8 will thus serve the function of a triple lock, as it not only secures the umbrella handle, but also the 85 sleeve and lower rod extension. It will at 85 the same time reinforce the connection between the handle and tubular rod, thus producing a more rigid structure at this point.

The lower rod extension or umbrella tip 3 is preferably provided with a groove or 90 key-way 17 and the tubular rod 2 with a key 18 to prevent any turning movement of the tip with connected links 14—15, etc. The tip or lower rod extension is furthermore 95 provided near its base with a fixed exterior cap 19 which fits down over the pivotal connection 4 of the ribs to form a water tight connection. It also acts as a stop to limit the inward movement of the tip and furthermore helps to secure the umbrella covering and protect it from injury at this point.

When it is desired to fold the umbrella, it is only necessary to depress latch 8, a notch 20 being formed in the sleeve to permit depression of the latch. The sleeve when 100 released is then pushed down on the tubular rod away from the handle and this movement is transmitted to eject the umbrella tip which is then folded over, as in Fig. 2. The handle is then extracted and the whole 105 structure may be placed in a covering and packed away in a short and compact space.

One of the chief advantages of the present construction is that the single locking or latching means provided by the detent 8 serves to lock the handle A, hollow rod 2 5 and sleeve 10 together into a rigid unitary structure; and that the release of the sleeve from the detent does not operate to sever the rigid connections between the handle and the remainder of the umbrella or 10 parasol.

Having thus described my invention what I claim and desire to secure by Letters Patent is—

In a folding umbrella, the combination 15 with a hollow rod, of a tip movable into and out of the lower end of the rod, links pivotally connected to the tip, a handle having a hollow rod extension removably engaged in the upper end of the rod, said extension 20 having a slot formed therein, a latch pivotally connected interiorly of the extension,

a sleeve slidably mounted on the rod, said sleeve and rod having registering slots which also register with the slot of the extension, said latch being adapted to engage 25 in said slots to hold the sleeve, rod and extension in fixed relation, said rod having a pair of slots formed therein, a pin slidably engaged in said slots and having its ends fixed to the sleeve, and a rod mounted interiorly of the hollow rod and having its lower end connected to the inner one of said links and its upper end connected centrally of said pin.

In testimony whereof I have hereunto set 35 my hand in the presence of two subscribing witnesses.

THOMAS SLATTER.
